UNITED STATES PATENT OFFICE

2,517,253

HAIR CURLING CLIP HEATER

Philip D. Spaeth, Cincinnati, Ohio

Application August 20, 1947, Serial No. 769,668

8 Claims. (Cl. 219—24)

1

2

The present invention relates to apparatus for use in the curling or permanent waving of human hair.

An object of the invention is to incorporate in such an apparatus improved means whereby the curling or permanent waving of the hair is performed in a superior manner, with a minimum of discomfort to the person undergoing the hair waving procedure.

Another object of the invention is to facilitate and expedite the curling or permanent waving operation, relieving the operator of strain and fatigue, and reducing the amount of skill required in forming a proper permanent wave.

A further object is to provide apparatus of the character referred to, which is not affected adversely by variations in room temperature, drafts, and other extraneous factors which ordinarily must be compensated for in equipment of other types in order to obtain the desired results incident to permanent waving of the human hair.

Another object of the invention is to provide apparatus of the character described above, which is highly durable, efficient, and simple in its operation, the arrangement being such that a relatively unskilled operator may produce a permanent wave comparable with that heretofore obtainable only by highly skilled and trained operators.

The foregoing and other objects are obtained by the means described herein and illustrated upon the accompanying drawings in which:

Fig. 1 is a perspective view of the improved apparatus for the curling or permanent waving of human hair.

Fig. 2 is a longitudinal cross-sectional view of the apparatus illustrated by Fig. 1.

Fig. 3 is a cross-sectional view taken on line 3—3 of Fig. 2.

Fig. 4 is a cross-sectional view taken on line 4—4 of Fig. 3.

Fig. 5 is a wiring diagram, showing the electrical connections required in the apparatus.

Fig. 6 is a schematic view in side elevation partially broken away in section showing a heater bar constructed in accordance with an embodiment of this invention.

The apparatus with which the present invention is concerned, is generally regarded as a pre-heat type of apparatus, that is, one in which the curling clips contain no heating elements or other means of generating heat during the curling operation. In the use of the present type of apparatus, the curling clips are placed upon electrically heated tubular elements that are kept at a proper temperature, the curling clips absorbing the heat of the tubular elements and retaining such heat for a sufficient period of time to complete the curling operation. The clips, once heated by convection upon the electrically heated tubular elements, are adapted to be transferred from the machine to the curls wound on curling

rods, the curls having been previously saturated with a permanent waving solution as is customary. The heated curling clips preferably are of metal of such quality and weight as will retain the necessary amount of heat to complete the permanent waving operation.

In apparatus of the character mentioned above, it is necessary to provide suitable means of elevating the temperature of the curling clips to a specified degree suitable for waving the hair. In order that the curling clips will be uniformly heated at all times, the machine must not be sensitive to changes in room temperature, drafts, and other extraneous conditions. The use of thermostats and similar devices for controlling pre-heat types of apparatus has generally been regarded as unsatisfactory, since the control equipment of that type is not in direct contact with the curling clips and therefore does not directly regulate the temperature of the clips.

With the device of the present invention, the electric heating element for the clips constitutes part of the control means for temperature, and by reason of that fact there is attained an immediate compensation for heat loss by the heating elements, as well as by the curling clips. Under this form of construction, no substantial variation in temperature of the curling clips can occur, irrespective of temperature conditions in the vicinity of the apparatus. It has never been possible to maintain the desired uniformity of temperature in the curling clips of pre-heat types of apparatus with the use of thermostats and the like.

With reference to the accompanying drawings, Fig. 1 illustrates a current form of the device, wherein the curling clips 12 are shown applied directly to the heating rods or bars 13 arranged in spaced parallelism within a case or housing 14. The clip supporting rods or bars are supported at opposite ends by means of a head member 15 and a foot member 16, so that they are rigidly supported and thereby constitute firm and substantial supports for the series of curling clips 12 applied thereto. The heating rods or bars have suitable connection with a source of electric current, and the amount of heat to be radiated thereby may be varied in any suitable manner, as by means of selector buttons 17, 18, and 19. By means of the several selector buttons, the operator may condition the controls for the heating rods or bars, to impart thereto a high, medium, or low temperature corresponding with the texture of the hair under treatment. Thus, the operator is assured of a satisfactory permanent wave, by simply determining whether the hair undergoing treatment may be classified as fine, medium, or coarse. The operator need exercise no control over time, voltage, or any of the other factors depending on the human element for success in the permanent waving of the hair.

Referring now to Fig. 2, it may be noted that

the heating rods or bars 13 are permanently fixedly mounted near their opposite ends 20 and 21, to the foot end member 16 and the head end member 15, respectively. For this purpose the ends of the rods or bars may be provided with stools 22 to which the bars or rods are welded or permanently fixed in any other suitable manner, the stools in turn being riveted or otherwise securely mounted upon the end members 15 and 16, as indicated at 23. The heating rods or bars preferably are arranged in a common plane and in spaced parallelism, as indicated, and they are of such proper diameter as to conveniently support the curling clips 12 with the heads of the clips in full face contact upon the rods or bars for inducing transfer of heat quickly and efficiently from the bars to the clip heads. The curling clips are provided with insulated finger grips 12A normally spring-separated to urge the clip jaws toward each other with substantial force, this being in accordance with common practice.

The heating rods or bars must be of a type which expand and contract lengthwise with changes of temperature. Because of its corrosion resisting characteristic, and its high coefficient of expansion, Monel metal may be used in forming the body of the rod or bar 13. The body of Monel metal preferably is of tubular form, and constitutes a sheath for heating elements disposed therein. In Fig. 6 a tubular rod 13a of this type is shown schematically. An insulated heating element 13b is located inside the rod 13a. As the temperature of the heating elements within the Monel metal rods or bars is increased, the rods or bars expand lengthwise to increase the distance between the head and foot end members 15 and 16, due to the fact that said members are securely fixed to the sheath. The distance between the head and member 15 and the foot end member 16, therefore will depend on the temperature of the heating rods or bars. Thus, the distance between the members 15 and 16 at any given temperature, is constant. The contraction and expansion of the heating rods or bars accordingly may be utilized to advantage in controlling the heating of the rods or bars and the curling clips normally supported thereon. To utilize the definite expansion and contraction characteristics of the heating rods or bars for controlling the temperature thereof, the head and foot end members 15 and 16 are mounted within the case or housing for relative movement toward and from one another. The head end member 15 may be bolted as at 24 or otherwise securely fixed to one or more supporting members 25 anchored to the ends of the case or housing at 26 and 27, while the foot end member 16 may be slidably supported thereon at the bracket 28. The bracket may consist merely of a metallic part apertured to slidably receive the supporting means 25. The supporting means accordingly have no restraining effect upon relative movement of the head and foot end members induced by expansion and contraction of the heating rods or bars 13.

At 30 is indicated a rod-like motion transmitting member supported in parallelism with the heating rods or bars 13, this member 30 being fixedly secured to the foot end member 16 in any suitable manner, as by means of clamping nuts 31 and 32. The motion transmitting member 30 is slidably supported by the head end member 15, by passing it through an aperture 33 formed therein. This member 30 may be in the form of a rod or tube or any suitable material having a very low coefficient of expansion, so that its

length is relatively unaffected by changes of temperature. Various materials are available in forming the motion transmitting member 30, and one such is a material commonly known as "invar." From the foregoing, it will be understood that the free end 34 of the motion transmitting member 30 will move in a straight line relative to the base 35 of the head end member, as the heating rods or bars 13 expand and contract lengthwise under changes of temperature. This relative movement of the end 34 of member 30 accordingly may be utilized in controlling flow of electric current through the heating rods or bars.

The manner of control is most readily evident by referring to Fig. 4, wherein is shown a connection between the free end 34 of the motion transmitting member 30, and a switch actuator 36 which may be in the form of a lever pivoted upon member 30 at the location 37. Lever 36 fulcrums against a pin 38 upstanding upon a bracket 39 fixed to the base 35. As the heating rods or bars 13 expand to move the foot end member 16 lengthwise of the supports 25, lever 36 will be moved about its fulcrum 38 by the action of the rodlike motion transmitting member 30. Motion of the lever in the opposite direction may be effected by a suitable spring 30, as will be explained. Accordingly, the free end 40 of lever 36 swings along an arc about the fulcrum 38 whenever changes occur in the temperature of the several heating rods or bars 13.

The lever 36 carries at its free end an adjusting screw 41 which is threaded into a threaded bore of the lever. The forward end 42 of the adjusting screw is adapted to approach and recede from a switch actuating pin or plunger 43 that extends from the side of the switch housing 44. Within the housing is a movable contact 45 of an electric switch, which contact normally is biased against a stationary contact 46. The switch has a second stationary contact 47 to be struck by the movable contact arm 45 as the switch plunger 43 is actuated. The electric switch referred to may be one of the type known commercially as a micro-switch.

The adjusting screw 41 may be set to various positions of extension laterally of the switch actuator lever 36, for the purpose of varying the position at which the lever will be effective to actuate the switch 44. For this purpose, the adjusting screw may be provided at one end with a pinion 48 or any other form of means to effect rotation of the adjusting screw.

As illustrated by way of example, in the accompanying drawings, pinion 48 is to be rotated for rotating the adjusting screw, by reason of its meshing with a gear segment 49 pivoted at 50 upon the head end member of the apparatus. The gear segment has a pin and slot connection 51 with a slide 52, which slide is to be moved to several definite positions within its longitudinal travel limits.

A suitable selector means is provided for use by the operator of the apparatus, to displace the slide 52 to the right or left of the intermediate position assumed by the slide in Fig. 3. Such means may be in the form of wedge plates 53, 54, and 55 which are attached to the several selector buttons 17, 18, and 19, respectively. By depressing the selector button 17 downwardly against its leaf spring 56, the incline of the wedge 53 strikes a roller or other abutment 57 carried by the side 52, thereby resulting in a shifting movement of the slide to the left in Fig. 3. The slide in moving to the left carries with it the gear sector 49, which rotates the adjusting screw and the pinion

48 in a counter-clockwise direction. This repositioning of the adjusting screw causes its free end 42 to retract from the switch plunger 43; thereby requiring the switch actuator arm or lever 36 to move a greater distance in order to actuate the switch contact 45.

By depressing the middle selector button 18 after the button 17 has been restored to its elevated position by the spring 56, the inclined edges of the middle wedge 54 will strike the roller 53 of the slide, to return the slide to the intermediate position of Fig. 3. The slide carries another roller 59, likewise acted upon by the wedge 54, to center the slide whenever the push button 18 is fully depressed. Upon depressing the selector button 19, wedge 55 strikes the roller 59 of slide 52, to displace the slide toward the right, which results in clockwise rotation of the adjusting screw 41 and its pinion 48. The adjusting screw when so rotated approaches the switch plunger 43, so that very little additional movement of lever 36 is required for actuating the switch.

The wedge elements 53, 54, and 55 are normally maintained in an elevated position by means of the springs 56 which yieldingly abut the stems 61 that extend through suitable apertures furnished in the base plate 35 of the head end member 15. Upward extensions of the stems carry the push buttons 17, 18, and 19.

The slide 52, as best illustrated by Fig. 4, may comprise a pair of spaced parallel side plates 62 and 63 having the several rollers or abutments 57, 58, 59, and 60 disposed between them. The lower edges of plates 62 and 63 may rest and slide upon the base 35 of the head end member. From the foregoing, it will be understood that actuation of switch 44 may be governed by the position of slide 52 as determined by the wedge members of the selector buttons.

As a means of indicating which of the selector buttons has been depressed, the member 15 is provided with several windows, one adjacent to each selector button, to register with similar windows carried by an indicator plate 64 that moves with the slide 52. The indicator plate may overlie the head end member as shown upon Figs. 1 and 3, and movement of the slide 52 may be imparted thereto by means of the upstanding brackets 65 having their upper and lower ends fixed to the indicator plate and to the slide, respectively.

The windows of the indicator plate are shown at 66, 67, and 68, and are so spaced apart as to properly register with the windows 69, 70, and 71 formed in the head end member 15, as the selector buttons for the respective windows are depressed. The windows of the indicator plate may carry suitable indicia such as the words "Fine," "Medium," and "Coarse." The words may be applied to suitable transparencies carried by the indicator plate 64, so that light rays from a lamp 72 beneath the indicator plate may illuminate the indicia as its corresponding windows are aligned by depressing the proper selector button. In Fig. 3, rays from the lamp 72 will pass upwardly through the registering windows 67 and 70, which previously were aligned by depressing the middle selector button 18. To align the windows 66 and 69, it is necessary to depress the selector button 17, whereas to align the windows 68 and 71, the selector button 19 would be depressed correspondingly moving the slide. As will be understood, each movement of the slide results in a predetermined rotational movement of the adjusting screw 41, which deter-

mines the electric current requirements of the apparatus.

The case or housing may be furnished with one or more carrying handles indicated at 76. A pilot lamp or other signal 77 is furnished for the purpose of informing the operator when the curling clips have reached a proper temperature, so that the clips may be removed from the heating rods or bars 13 for use in the permanent waving operation. The function and operation of the pilot lamp will be explained in greater detail hereinafter.

Referring to the wiring diagram of Fig. 5, 81 and 82 indicate the electric supply conductors for energizing the apparatus. The indicator lamp 72 is connected across these conductors by means of the wire 83, so that whenever the main switch 84 is closed, the lamp will be energized to illuminate one of the several indicia previously referred to herein. Conductor 81 is common to the corresponding ends of all the heating rods or bars 13, so that electric current may pass from conductor 81, through all of the heating rods or bars, and find its return by way of a conductor 85 that has connection with the opposite ends of all the rods or bars 13. The circuit of the rods or bars is open at the relay contact 86, except when the main switch 84 is closed. Upon closing the main switch, however, current may flow through conductors 82, 87, and 88, to the micro-switch contacts 46 and 45, the latter being connected to the return conductor 81 by means of the connection at 89. The circuit which is described includes the winding of the relay 90, energization of which effects a closing of the relay switch 86. Accordingly, a flow of electric current will be established through all of the heating rods or bars 13 by way of the conductors 82, 86, 85, 13, and 81.

It will be recalled that heating of the rods or bars 13 induces elongation thereof, so that the motion transmitting member 38 is pulled to the right in Fig. 5, for swinging the switch actuator 36 arcuately in clockwise direction about the fulcrum 38.

When the apparatus is cold, the adjusting screw 41 is held in contact with the switch actuating pin or plunger 43 by means of the leaf spring 80, to hold the movable contact 45 against the stationary contact 46 of the micro-switch. The adjusting screw will leave the switch pin or plunger 43 when the heating rods or bars 13 reach a predetermined temperature, but the instant at which this occurs is determined by the position of the lever 36 upon the adjusting screw, as determined by the depression of the selector buttons 17, 18, and 19, this having been explained previously in describing the function of the gear sector 49, slide 52, and the several selector button wedges.

As the heating rods or bars 13 reach the desired temperature, the adjusting screw 41 will be retracted from the switch pin or plunger 43 by the rocking movement of lever 36, thereby permitting the micro-switch movable contact 45 to swing against the opposite stationary contact 47. When this occurs, an electric circuit is completed through the conductors 81, 89, 45, 47, 91, 92, relay coil 93, conductor 94, and the supply conductor 82. The resulting energization of the relay 93 effects a closing of the relay contacts 95 and 96, so that current may flow through the pilot lamp 77 by way of conductors 81, 99, 77, 98, 96, 100, and 82. At the same time, the energizing circuit for the heating rods or bars 13 is broken at the relay switch contact 86, due to the breaking of

the relay coil circuit of relay 90, at the micro-switch contact 46. Thus, no current will flow through the heating rods or bars 13 until they are reduced in temperature sufficiently to permit swinging of the lever 36 in counter-clockwise direction to the extent of depressing the switch plunger 43, and thereby moving the contact arm 45 against the stationary contact 46. Such closing of the micro-switch at 45-46 re-establishes the circuit through the main relay winding 90, for closing the relay switch contact 96 and restoring the heating circuit.

It will be noted that the foregoing making and breaking of the heating circuit for the clip heating rods or bars 13 may continue indefinitely, or as long as the main switch 84 is closed. Moreover, the pilot lamp 77 will remain energized throughout such indefinite period, since its holding relay 93 is never de-energized except upon breaking the circuit at the main switch 84. In other words, once the coil of relay 93 is energized to close the contacts 95 and 96, movements of the micro-switch contact 45 cannot influence the closed contacts 95 and 96 as these are held closed by the relay coil circuit 81, 97, 95, 92, 93, 94, 82 and 84.

As will be understood, the movable contact 45 of the micro-switch is biased by spring means or otherwise, always toward the stationary contact 47, the bias being overcome by depression of the actuating pin or plunger 43 of the switch under the force of spring 80. Whenever the lever 36 is swung in the direction of spring 80 by the action of the motion transmitting member 30, the resultant release of pressure upon the pin or plunger 43 permits the movable contact 45 of the micro-switch to assume its normal position against the stationary contact 47.

From the foregoing it will be understood that the control for maintaining a given temperature of the heating rods or bars 13, is completely automatic and may not be disturbed by the operator of the apparatus. The control is regulated directly from the heating rods or bars themselves, so that any outside interference such as a draft directed toward the apparatus will immediately affect the heating rods or bars and cause them to promptly compensate for the resulting change of temperature in proximity thereto. By so rendering the heating rods or bars themselves sensitive to changes in surrounding temperature, the curling clips supported thereon will necessarily be kept at a proper temperature for application to the curls undergoing treatment. It is therefore impossible to bring about overheating or underheating of the curling clips, even through the apparatus may be exposed to sudden changes of room temperature.

As previously stated herein, the operator of the present apparatus need exercise no control whatever over time, voltage, or any of the other factors subject to human error, in the performance of the hair waving operation. Success of the operation is thereby assured, even though the operator may be unskilled or indifferent to the requirements of the procedure.

It should be understood that the apparatus herein disclosed is subject to various modifications and changes in structural details, as it is obviously possible to effect various substitutions and equivalents in the construction of the apparatus. The row of apertures 101 to the left of the selector buttons 17, 18, and 19 shown upon Fig. 1, provides for the escape of heat from the head ends of the heating rods or bars 13.

What is claimed is:

1. A hair curling clip heater comprising in combination, a plurality of longitudinal heater bars subject to elongation upon heating, said bars being substantially parallel and dimensioned to support thereon a plurality of displaceable curling clips in heat transferring relationship, a head end member and a foot end member spaced apart, and means fixing opposite end portions of the heater bars securely to said end members whereby expansion of the bars increases the distance between said end members, a motion transmitting means in the form of an elongated actuator bar relatively immune to elongation when heated, means fixing one end only of said actuator bar to one of said end members, leaving the opposite end of the actuator bar free for relative longitudinal movement with respect to the other end member, electrical circuit means including a source of electricity and a switch for controlling a flow of electricity through the heater bars, and means associated with said actuator bar for opening and closing the switch and the circuit controlled thereby.

2. A hair curling clip heater comprising in combination, a plurality of longitudinal heater bars subject to elongation upon heating, said bars being substantially parallel and dimensioned to support thereon a plurality of displaceable curling clips in heat transferring relationship, a head end member and a foot end member spaced apart, and means fixing opposite end portions of the heater bars securely to said end members whereby expansion of the bars increases the distance between said end members, a motion transmitting means in the form of an elongated actuator bar relatively immune to elongation when heated, means fixing one end only of said actuator bar to one of said end members, leaving the opposite end of the actuator bar free for relative longitudinal movement with respect to the other end member, electrical circuit means including a source of electricity and a switch for controlling a flow of electricity through the heater bars, and means associated with said actuator bar for opening and closing the switch and the circuit controlled thereby.

3. A hair curling clip heater comprising in combination, a plurality of longitudinal heater bars subject to elongation upon heating, said bars being substantially parallel and dimensioned to support thereon a plurality of displaceable curling clips in heat transferring relationship, a head end member and a foot end member spaced apart, and means fixing opposite end portions of the heater bars securely to said end members whereby expansion of the bars increases the distance between said end members, a motion transmitting means in the form of an elongated actuator bar spaced below the heater bars and relatively immune to elongation when heated, means fixing one end only of said actuator bar to one of said end members, leaving the opposite end of the actuator bar free for relative longitudinal movement with respect to the other end member, an electric circuit including the heater bars, a source of electricity, and a circuit controlling

60 electric switch, and means responsive to relative movements occurring between the free end of the actuator bar and said other end member, for operating the switch to open and close the electric circuit.

4. A hair curling clip heater comprising in combination, a plurality of longitudinal heater bars subject to elongation upon heating, said bars being substantially parallel and dimensioned to support thereon a plurality of displace-

able curling clips in heat transferring relationship, a head end member and a foot end member spaced apart, and means fixing opposite end portions of the heater bars securely to said end members whereby expansion of the bars increases the distance between said end members, a motion transmitting means in the form of an elongated actuator bar spaced below the heater bars and relatively immune to elongation when heated, means fixing one end only of said actuator bar to one of said end members, leaving the opposite end of the actuator bar free for relative longitudinal movement with respect to the other end member, an electric circuit including the heater bars, a source of electricity, and a circuit controlling electric switch, and means responsive to relative movements occurring between the free end of the actuator bar and said other end member, for operating the switch to open and close the electric circuit, and an adjusting device selectively operative to retard and advance the operation of the switch by said responsive means.

5. A hair curling clip heater comprising in combination, a plurality of longitudinal heater bars subject to elongation upon heating, said bars being substantially parallel and dimensioned to support thereon a plurality of displaceable curling clips in heat transferring relationship, a head end member and a foot end member spaced apart, and means fixing opposite end portions of the heater bars securely to said end members whereby expansion of the bars increases the distance between said end members, a motion transmitting means in the form of an elongated actuator bar spaced below the heater bars and relatively immune to elongation when heated, means fixing one end only of said actuator bar to one of said end members, leaving the opposite end of the actuator bar free for relative longitudinal movement with respect to the other end member, an electric switch, a source of electricity, and an electric circuit including the heater bars, the switch, and the source of electricity, said switch being opened and closed by movements of the free end of said actuator bar.

6. A hair curling clip heater comprising in combination, a plurality of longitudinal heater bars subject to elongation upon heating, said bars being substantially parallel and dimensioned to support thereon a plurality of displaceable curling clips in heat transferring relationship, a head end member and a foot end member spaced apart, and means fixing opposite end portions of the heater bars securely to said end members whereby expansion of the bars increases the distance between said end members, a motion transmitting means in the form of an elongated actuator bar spaced below the heater bars and relatively immune to elongation when heated, means fixing one end only of said actuator bar to one of said end members, leaving the opposite end of the actuator bar free for relative longitudinal movement with respect to the other end member, an electric switch, a source of electricity, and an electric circuit including the heater bars, the switch, and the source of electricity, said switch being opened and closed by movements of the free end of said actuator bar, and means included in the electric circuit for indicating a heated condition of the clip-supporting heater bars.

7. A hair curling clip heater comprising in combination, a plurality of longitudinal heater bars subject to elongation upon heating, said

bars being substantially parallel and dimensioned to support thereon a plurality of displaceable curling clips in heat transferring relationship, a head end member and a foot end member spaced apart, and means fixing opposite end portions of the heater bars securely to said end members whereby expansion of the bars increases the distance between said end members, a motion transmitting means in the form of an elongated actuator bar spaced below the heater bars and relatively immune to elongation when heated, means fixing one end only of said actuator bar to one of said end members, leaving the opposite end of the actuator bar free for relative longitudinal movement with respect to the other end member, an electric circuit including the heater bars, a source of electricity, and a circuit controlling electric switch, and means responsive to relative movements occurring between the free end of the actuator bar and said other end member, for operating the switch to open and close the electric circuit, and an adjusting device selectively operative to retard and advance the operation of the switch by said responsive means, and means included in the electric circuit for indicating heated conditions of the clip-supporting heater bars as determined by said adjusting device.

8. A hair curling clip heater comprising in combination, an elongated heater bar subject to elongation upon heating and adapted to support thereon a plurality of detachable curling clips in heat transferring relationship therewith, spaced head and foot members, and means for rigidly securing the ends of the heater bar to said respective head and foot members whereby relative movement between said end members results in response to changes in length of said bar, a motion transmitting means comprising an elongated actuator bar spaced from the heater bar and relatively immune to elongation when heated, one end of said actuator bar being secured to one of said members and the other end being movable with respect to the other member in response to changes in length of said heater bar, electrical circuit means including a switch for controlling a flow of heating current for said heater bar, and means associated with said actuator bar for opening and closing the switch.
